SWIMMING MASK

Joseph V. Ferriot, Akron, Ohio, assignor to Auburn Rubber Company, Inc., Auburn, Ind., a corporation

Filed Mar. 4, 1960, Ser. No. 59,615

Term of patent 14 years

(Cl. D83—1)

Fig. 1 is a perspective view of a swimming mask, showing my new design.

Fig. 2 is a top plan view thereof.

Fig. 3 is a side elevation view thereof.

Portions of the strap element are broken away in Figs. 2 and 3 for convenience of illustration only.

My design for a swimming mask is characterized by the specific slotted head strap element in association with the arcuate, generally oval-shaped eye and nose covering element, all as shown.

I claim:

The ornamental design for a swimming mask, as shown and described.
